UNITED STATES PATENT OFFICE.

JAMES H. FLEMING, OF NEWARK, NEW JERSEY, ASSIGNOR TO THE NATIONAL DAIRY MACHINE COMPANY, OF NEW JERSEY.

THRUST-BEARING.

SPECIFICATION forming part of Letters Patent No. 663,383, dated December 4, 1900.

Application filed January 11, 1900. Serial No. 1,036. (No model.)

To all whom it may concern:

Be it known that I, JAMES H. FLEMING, a citizen of the United States, residing at Newark, in the county of Essex and State of New Jersey, have invented certain new and useful Improvements in End Bearings for Rotary Shafts; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The objects of this invention are to provide a support or bearing for the end of a vertical rotating shaft, to provide a bearing which will offer less frictional resistance to the turning of the shaft than those heretofore in use, to thereby reduce the loss of power due to friction, and to secure other advantages and results, some of which may be referred to hereinafter in connection with the description of the working parts.

The invention consists in the improved end bearing for rotary shafts and in the arrangements and combinations of parts of the same, all substantially as will be hereinafter set forth, and finally embraced in the clauses of the claim.

Referring to the accompanying drawings, in which like letters of reference indicate corresponding parts in each of the several views, Figure 1 is a vertical section of my improved bearing and a portion of the shaft, taken at right angles to the plane of the supporting-disks. Fig. 2 is a side view of the same. Fig. 3 is an edge view with reference to the planes of the disks, showing a modified form of construction, partly in section; and Fig. 4 is a side view of the same.

In said drawings, *a* indicates a rotary shaft having in the end thereof a cavity or socket *b* in the form of a cone or the frustum of a cone, said socket lying axially coincident with the longitudinal axis of the shaft *a* and having its inclined side walls flaring outwardly and toward the end of the shaft. Said socket *b* receives a ball *c* of about the diameter of the wider end or mouth of the socket, the periphery of the ball being adapted to engage

the walls of the socket somewhat back from the mouth. The ball *c* in turn rests on and is supported by the oppositely-beveled peripheries of two disks *d d*, lying in parallel planes and adapted to turn oppositely on the same axial center. Said disks lie closely adjacent to one another, so that their oppositely-beveled peripheries together form a flaring annular groove on which the ball *c* lies, so that it cannot slip in either direction laterally over the edges of the disks.

To prevent the ball *c* from moving in either direction in the groove in the plane of the disks, bearing-wheels *i* are arranged at both sides of the ball. These bearing-wheels are pivoted at the ends of brackets or arms *j*, projecting from the shaft or support for the disks, and have their peripheries in contact with opposite points on the ball to keep it from moving longitudinally in the groove.

The disks are preferably centrally perforated to loosely receive a supporting-shaft *e*, and at the outer sides of said disks on said shaft are disk-holding plates *f f*. The shaft *e* has a shoulder or projecting flange *g*, against which one holding-plate is forced or arranged. The inner face of said holding-plate and the contiguous face of the adjacent disk have each an annular groove, preferably triangular in cross-section and at equal distances from the center, which grooves form races for balls *p*, arranged between said plates and disk. Similar ball-races are provided between the two disks to receive balls *p'* and *p''* between the outer disk and the second holding-plate to receive balls *p''*, the grooves on opposite sides of the same disk being of different radial distance from the center, so as to not greatly weaken the disk. The outer plate is screwed upon the shaft, which is threaded to receive it, and thus adjustment of the ball-races may be had by tightening or loosening this said outer disk. A lock-nut *h* serves to hold said parts in the proper relation when they have been once adjusted.

In Fig. 3 I show a modification of construction in which the single solid shaft and independent holding-plates are dispensed with, as well as the central perforations in the disks. In this form or construction at the outer sides of the disks *d d* are central bosses *k*, the slop-

ing or inclined sides of which form cone bearing-surfaces for the balls. At each side of the two disks are heavy tubular shaft-sections *l l*, axially coincident with said disks.

5 The ends of the shaft-sections next to the disks are recessed, as at *m*, to form races for the balls *n*. Said shaft-sections *l* are threaded exteriorly and screw toward each other in the opposite arms of a U-shaped supporting-plate *o*. Said sections are screwed inwardly toward each other until the proper adjustment of the ball-bearings is secured and are then held in position by lock-nuts *h'*, arranged on said sections. The adjacent faces of the 15 disks *d* are grooved, as at *q*, to receive balls which form a bearing between the two disks.

From the foregoing description the operation of the device is apparent. As the shaft *a* rotates the ball *c* turns upon a vertical 20 axis, causing the two disks to revolve in opposite directions. The various bearings offer very little frictional resistance, and the shaft turns easily and with little loss of power.

Having thus described the invention, what 25 I claim as new is—

1. The combination with the rotary shaft and ball *c*, of a pair of oppositely-movable disks supporting said ball, and supports for said oppositely-movable disks, substantially 30 as set forth.

2. The combination with the rotary shaft, disks *d*, *d*, adapted to rotate in opposite directions, and having balls interposed therebetween and plates *f*, *f*, arranged outside of 35 said disks and balls interposed between said disks and plates, substantially as set forth.

3. The combination with a rotary shaft, of a pair of beveled disks for supporting said shaft, balls holding said disks in parallel 40 planes, balls arranged between said disks to hold the same apart, and supports providing raceways for the first said balls, the said disks being beveled and together forming a groove, substantially as set forth.

45 4. The combination with the shaft having

a recessed lower end, a ball supporting said shaft, beveled disks supporting said ball, bearing-wheels *i*, *i*, for holding the ball in the groove formed by said beveled disks and means for holding said disks in operative position substantially as set forth.

5. The combination with a rotary shaft, and a ball, *c*, of disks *d*, *d*, balls *p*, *p'*, and *p''* and plates *f*, all arranged and adapted to operate, substantially as set forth.

6. The combination with the rotary shaft *a*, and a ball *c*, supporting the same, of disks beveled at their peripheries to receive the ball *c*, and having raceways on opposite sides, plates *f*, also having raceways, and balls disposed between the disks and between the disks and plates, substantially as set forth.

7. The combination with the rotary shaft *a*, of disks, each beveled at its periphery and provided with raceways on opposite sides, 65 balls interposed between the disks, plates disposed near the outer sides of said disks and having raceways, balls interposed between the plates and disks, a shaft *e*, supporting said plates and means for adjusting 70 said plates on said shaft, substantially as set forth.

8. The combination with the rotary shaft *a*, of disks movable in opposite directions and provided with raceways on opposite sides, 75 balls interposed between the disks, plates disposed near the opposite outer sides of the disks and having raceways, and one of said plates being threaded, balls interposed between the plates and disks, a shaft extending 80 through said plates and disks, said shaft having a shoulder *g*, and threads to receive the threaded plate, substantially as set forth.

In testimony that I claim the foregoing I have hereunto set my hand this 9th day of 85 September, 1899.

JAMES H. FLEMING.
